CLAIM

The ornamental design for a strength indicator for hand grip strengthener as shown and described.

DESCRIPTION

FIG. 1 is a perspective view of a strength indicator for hand grip strengthener showing my new design;

FIG. 2 is a front elevation view thereof;

FIG. 3 is a front view showing my new design, with the strength indicator for hand grip strengthener showing a resistance force value;

FIG. 4 is a front view showing my new design, with the strength indicator for hand grip strengthener showing a different resistance force value; and,

FIG. 5 is an enlarged perspective view of detail "5" identified in FIG. 1.

The broken lines are directed to environment and form no part of the claimed design.

1 Claim, 5 Drawing Sheets
